UNITED STATES PATENT OFFICE

110,885

DESIGN FOR A COMBINED PIPE AND IDENTIFICATION SLIP HOLDER

Edward M. Springer and Victor E. Harris,
Huntington Park, Calif.

Application September 21, 1937, Serial No. 71,712

Term of patent 3½ years

To all whom it may concern:

Be it known that we, Edward M. Springer and Victor E. Harris, citizens of the United States and residents of the city of Huntington Park, county of Los Angeles, State of California, have invented a new, original, and ornamental Design for a Combined Pipe and Identification Slip Holder, of which the following is a specification, reference being had to the annexed drawing, forming a part thereof.

Fig. 1 is a side view of a combined pipe and identification slip holder showing our new design;

Fig. 2 is a top view thereof; and
Fig. 3 is an end view thereof.

We claim:

The ornamental design for a combined pipe and identification slip holder, as shown.

EDWARD M. SPRINGER.
VICTOR E. HARRIS.
